(57) **CLAIM**

The ornamental design for an automobile film as shown and described.

DESCRIPTION

FIG. 1 is a top plan view of an automobile film showing my new design, and a reverse view thereof with no pattern is omitted; and,

FIG. 2 is an enlarged view of a portion identified in rectangle 2 of FIG. 1.

The broken lines depict the boundaries of the claimed design and form no part thereof.

1 Claim, 2 Drawing Sheets

FIG. 1

FIG. 2
